SUCTION CLEANER

Vernon E. Carlson, Canton, Ohio, assignor to The Hoover Company, North Canton, Ohio, a corporation of Ohio

Application March 6, 1939, Serial No. 260,000

4 Claims. (Cl. 306—13)

The present invention relates to suction cleaners and particularly to new and improved handle locking mechanism in a suction cleaner. More specifically the invention comprises an improved handle control in a suction cleaner which is characterized in that the handle is locked in the selected position when the cleaner is lifted off the floor.

It is an object of the present invention to provide a new and improved suction cleaner. It is another object to provide new and improved handle locking means in a suction cleaner. A further object is to provide a handle control device which resistsingly maintains the handle in different positions and also positively locks the handle in the different positions when the cleaner is lifted off the floor. Further objects and advantages of the invention will be apparent upon referring to the following specification and claims and attached drawings wherein:

Figure 1 is a side elevation with parts broken away of a suction cleaner embodying the present invention;

Figure 2 is a section along the line 2—2 of Figure 1, and

Figure 3 is a view similar to Figure 1, but showing the cleaner raised off the supporting surface and the handle positively locked with respect to the cleaner casing.

An embodiment of the invention is disclosed in a suction cleaner comprising a main casing 10 having a nozzle 11 communicating with an air passageway 12 extending to a fan chamber 13 communicating with an exhaust passageway 14 discharging into a dust bag 15 attached to a vertical flange 16 at the extreme end of the exhaust passageway 14. The casing 10 supports an unshown motor enclosed in a housing 17, the motor operating a fan 18 to create suction and to draw dirt-laden air from the surface being cleaned through the nozzle 11 and suction passageway 12 into the fan chamber 13, and discharges the same through the exhaust passageway 14 into the dust bag 15. A carpet engaging member 20 is rotatably mounted in the nozzle 11 and is driven by a belt 21 extending to a pulley 22 rigidly secured to the armature shaft of the motor. The cleaner is supported on front and rear wheels 23 and 24 respectively, the latter being journaled on a shaft 25 rigidly carried by a pair of spaced ears 26 formed integrally with a rear caster assembly 27.

The rear caster assembly 27 comprises a substantially U-shaped frame provided with a back wall 28 and side arms 30 and 31. The caster

extends transversely beneath the rear end of the casing 10 and its side arms are pivoted on a rod 32 supported at its outer ends in a pair of lugs 33 depending integrally from the bottom wall 34 of the casing 10. A torsion spring 35 is coiled around the rod 32 and has one end 36 anchored against the bottom wall 34 of the cleaner casing, and its other end 37 exerts pressure upon the back wall 28 of the caster 27 in a direction to rotate the latter counterclockwise on its supporting rod 32, as viewed in Figures 1 and 3. The torsion spring 35 operates to raise the rear portion of the cleaner upwardly to tilt the nozzle portion downwardly when the cleaner rests on the floor, and counterbalances the normal cleaner load on the rear wheels 24. When the cleaner is bodily lifted from the floor the caster 27 is pivoted counterclockwise as viewed in Figures 1 and 3 by the action of the spring 35 and due to the influence of gravity.

The cleaner is propelled over the surface being cleaned by a handle 40 which is removably attached in a split handle socket 41 having a front wall 42, a rear wall 43 and opposing side walls 44. The handle socket is journaled on a pivot pin 45 which extends through the socket side walls 44 and is rigidly mounted in the spaced side walls 46 of a handle bracket 47. The rear wall 43 of the handle bracket is secured to the exhaust flange 16 and the lower lateral edges 49 of the bracket side walls 46 are mounted on the cleaner casing above the exhaust passageway 14. One of the side walls of the handle socket 41 extends below the pivotal axis 45 and is provided with a segmental member 50 comprising an arcuate face or edge 51 having seats or recesses 52 and 53 at opposite ends thereof, and a central recess 54 which covers a considerable extent of the face 51. A plurality of stops 55, 56, 57 and 58 define the segmental recesses and limit the range of movement of the handle 40 when the latter is in different operating positions.

Adapted to engage the segmental surface 51 is a roller detent 60 journaled on a pin 61 rigidly supported in a pair of spaced arms 62 formed integrally on a detent lever 63. The lever 63 is pivotally supported on a pin 64 having one end supported in an L-shaped member 65 which is integral with the handle bracket 47 and the opposite end of the pin 64 is mounted in a side wall of the handle bracket. A torsion spring 66 is arranged about the pin 64 and has one end 67 anchored against a flange 68 formed on the handle bracket, and its opposite end 69 seats against the detent or control lever 63. The spring

66 tends to at all times urge the roller detent 60 into engagement with the segmental surface 54 to resistingly maintain the handle in its adjusted position. When the roller detent 60 is disposed in the segmental seat 53 the handle is resistingly held in the vertical position shown in Figure 1, and when the roller detent is in the segmental seat 52 the handle is resistingly held in a substantially horizontal position, the recess portion 54 is of such extent that when the roller detent 60 engages it the handle is permitted to freely pivot through a substantial range which corresponds to the normal operating range of handle movement.

When the handle is mounted at the rear end of the cleaner the weight of the latter is concentrated forwardly of the pivotal axis of the handle, and consequently when the cleaner is lifted off the floor the nozzle tends to pivot downwardly with respect to the handle. The usual handle control means do not function to prevent the front end of the cleaner from tilting downwardly with respect to the handle when the cleaner is lifted off the floor. In order to prevent such movement, I have provided a positive locking mechanism which functions when an upward lifting force is exerted on the handle, and comprises a lever 70 formed integrally with the side arm 30 of the rear caster 21, the latter operating as a lever about the pivotal axis 32. The locking lever 70 extends upwardly through an elongated slot 71 in the wall of the cleaner casing and is provided at its upper end with a laterally extending locking member 72 which is normally disposed forwardly of the detent lever 63 as shown in Figure 1 to permit free pivotal movement of the detent lever 63 when the handle 40 is rotated about its pivot 45. The locking member 72 is provided with a curved surface 73 which is adapted to pass beneath and abut the lower surface 74 of the detent lever 63 to prevent movement of the latter and lock the roller detent 60 in any one of the recesses 52, 53 or 54 to thereby lock the handle rigidly with respect to the cleaner casing when the latter is lifted off the floor.

In operation, assume that the handle is in the position shown in Figure 1, and it is desired to lower the handle, the operator merely exerts a slight downward pressure on the handle which causes the latter to pivot about the pin 45 against the resisting force exerted by the torsion spring 66. Movement of the handle downwardly causes the lever 63 to pivot clockwise, as viewed in Figures 1 and 3, and displaces the roller detent 60 from the recess 53, and the spring 66 urges the roller detent 60 into the recess 54 to permit free movement of the handle over a considerable operating range between the stops 56 and 57. The resisting force exerted by the spring 66 is sufficient to prevent the handle 40 from moving downwardly past the stops 56 and 57. If it is desired to move the handle to the lowest operating position the operator merely exerts a force on the handle which causes the roller detent 60 to move past the stop 56 into the recess 52, to thereby hold the handle in substantially horizontal position. In order to raise the handle the operator merely moves the handle upwardly to the desired position against the resisting force exerted by the torsion spring 66.

If the handle 40 is in the storage position shown in Figure 1, and the cleaner is lifted bodily off the floor, the weight of the cleaner is removed from the spring 35 which exerts a force to ro-

tate the locking lever 70 about its pivotal axis 32 in a counter-clockwise direction as viewed in Figures 1 and 3, causing the locking member 72 to move beneath the detent lever 63 to abut the lower wall 74 of the latter to thereby prevent rotation of the detent lever 63 and thus rigidly lock the roller detent 60 in the recess 53 preventing relative rotation between the handle 40 and the cleaner casing 10. This locking action takes place as the cleaner weight is being removed from the rear wheels 24 which causes the latter to pivot and move the locking lever 70 into abutment with the lever 63 before the cleaner is completely lifted off the supporting surface. When the cleaner is again placed on the floor the weight of the cleaner will move the wheels 24 toward the rear end of the cleaner casing 10 and pivot the locking lever 70 clockwise about the pivot 32 as viewed in Figure 3, causing the locking member 72 to move out of abutment with the lower wall 74 of the detent lever 63 whereby the latter is free to pivot about its pivotal axis 64 to permit normal operation of the cleaner handle.

If the roller detent 60 is disposed in the segmental recess 54, that is, when the handle is at a substantially 45° operating position, and the operator lifts the cleaner off the floor, the locking member 72 will move into engagement with the detent lever 63 to prevent rotation of the latter and the casing 10 will move downwardly with respect to the handle 40 in a limited range until the roller detent 60 engages the stop 56 to positively lock the handle relative to the casing 10.

It is to be understood that the protection herein applied for is not confined to the particular combinations of features or elements set out in the following claims. Protection is herein applied for, for any one or more of the features or elements referred to in the following claims, or described in the foregoing specifications or shown in the accompanying drawings, either independently or in combination.

I claim:

1. In a suction cleaner, a casing, lever means pivoted on said casing, wheels on said lever means to support said cleaner on a surface, a handle pivoted on said casing, handle control means for resistingly maintaining said handle in different operating positions relative to said casing, said lever means being movable into engagement with said control means to lock the latter to prevent movement of said handle with respect to said casing, said lever means being actuated into said locking engagement with said control means when the weight of said cleaner on said wheels and lever means is reduced by exerting an upward lifting force on said cleaner.

2. In a suction cleaner, a casing, a handle pivoted on said casing, segmental means having spaced recesses of different lengths representing different extents of range of handle movement, resiliently actuated detent means adapted to engage said segmental means to resistingly prevent pivotal movement of said handle beyond the angular range defined by the recess in which said detent means is positioned, and means for locking said detent means in any of the selected recesses to positively lock said handle with respect to said casing, and means to actuate said locking means upon lifting said cleaner from its supporting surface.

3. In an ambulatory machine, a casing, bracket means pivotally mounted on said casing and

movable with respect thereto when the weight of said machine is removed therefrom, wheels carried by said bracket means to support said machine on a supporting surface, a handle pivoted on said casing, and coacting handle locking means connected to said handle and bracket means and actuated by said movement of said bracket means to lock said handle with respect to said casing.

4. In a suction cleaner, a casing, bracket means pivotally mounted on said casing, wheels carried by said bracket means to support said cleaner

5 on a supporting surface, tension means acting on said casing and bracket means to counterbalance the normal cleaner load on said wheels, said tension means operating to pivot said bracket means when the cleaner weight on said wheels is reduced by exerting a lifting force on said cleaner, and coacting handle locking means connected to said handle and bracket means and actuated by said movement of said bracket means to lock said handle with respect to said casing.
